UNITED STATES PATENT OFFICE.

GEORGE PLAYFORD AND GEORGE RICHARD SWAINE, OF CLEVELAND, OHIO:
SAID SWAINE ASSIGNOR TO CHARLES F. ALAXANDER, OF SAME PLACE

SMOKE-PREVENTING FURNACE.

SPECIFICATION forming part of Letters Patent No. 297,630, dated April 29, 1884.

Application filed June 29, 1883. (No model.)

To all whom it may concern:

Be it known that we, GEORGE PLAYFORD and GEORGE R. SWAINE, both of Cleveland, in the county of Cuyahoga and State of Ohio, have invented new and useful Improvements 5 in Smoke-Preventing Furnaces, of which the following is a specification.

This invention relates to coal-burning furnaces, and has for its object to prevent the accumulation 10 of smoke by the complete combustion of all the fuel. This is accomplished by providing an endless traveling grate and an automatic self-feeding device, whereby the fuel is fed in a steady stream in small quantities in 15 such a manner that the fuel and all its gases are burned.

Our improvements relate to the traveling grate; and it consists in the construction and arrangement of the grate-bars and the mechanism 20 for carrying them and supporting them on a truck or carriage, as hereinafter described and claimed.

In the accompanying drawings, Figure 1 is a side elevation of our improved endless traveling grate as seen in place under a boiler. Fig. 2 is a front elevation of the same. Fig. 3 is a top or plan view of a portion of the grate-bars. Fig. 4 is a detached view of one of the grate-bars. Fig. 5 is a detached view 25 of one of the sprocket-wheels. Fig. 6 is one of the central supporting-rollers.

A is the under side of a boiler; B, a bridge-wall at back of fire-place. Within the said fire-place we supply a carriage or truck, C, running on suitable rails or track laid on the floor of said fire-place. In the upper corners of said carriage-frame are journaled shafts carrying the sprocket-wheels, each D D', and at suitable intervals between said shafts are placed other shafts, E E', journaled in the sides 35 of the frame. These shafts carry each a wheel or roller, e, for supporting the central part of the traveling grate.

F F' are two series of grate-bars, the individual bars of which have links f f' on each end, by which they are coupled together. Every alternate bar has its link nearer the end of the bar than its mate, as seen at f', Fig. 3. This arrangement gives a space for the sprockets 40 on the wheels D to engage with the links for propelling the grate. The pivots which

join the bars to one another consist of rods, f'', each of which extends the full width of the grate and passes through all the links of the contiguous bars of both series, between which bars said rod is situated. Firmness and simultaneous movement are thus insured to the grate, though made of two or more series of bars, said continuous pivots f'' serving to connect the different series of bars. 55

I do not consider it essential to the operation of my invention that all of the pivots should be made continuous and connect the different carriers or series of bars, as a fewer number—as every other one—might be sufficient to accomplish the above-mentioned results, the bars at the other points of pivoting being connected in any preferred manner. In the drawings two rows of bars are shown; but this number may be modified to one or more, as may be desired. 60 65 The middle supporting-rollers are not provided with sprockets, but have notches in the edges of their peripheries for the link-joints to work, to prevent a jumping movement the grate would have without this provision. The front shaft extends beyond the frame, and is provided with a gear and worm, G, by which motion is imparted from suitable power source for propelling the grate. To the boiler-front is made a hopper for containing fuel, the bottom of which sets over the front end of the grate. The opening through which the fuel is fed is regulated by a sliding door, H, by which the quantity supplied to the fire is governed. 70 75 80

At the back part of the fire-place is made a chamber for catching the clinker and cinders, consisting of a partition, I, having a curved upper part, over which the clinker is discharged from the grate. The said partition is 85 provided with a door, J, at the bottom, for allowing the clinker and cinders to be raked out when required.

These grate-bars are simple in construction, are easily coupled together, and in case of repairs are readily removed or replaced by new ones. 90

The principle upon which this grate is operated is that the fuel is fed no faster than it can be consumed, so that all the gases and smoke are burned. All the gases that are eliminated by the incoming fuel must pass over 95 100

the live fire at the rear portion of the grate, and are therefore consumed. The grate is also protected from being soon burned out, from the fact that it is in constant motion, and one-half the time each bar is traveling under side in the truck away from the fire, and is thereby given time and opportunity to cool down. The grate will therefore last much longer.

- Having described our invention, we claim—
- 10 1. The herein-described traveling grate, consisting of the combination of two or more series of transverse bars, the bars of each series being pivotally connected to form an endless carrier, and the different series connected by means, substantially as described, whereby the unity of the grate is insured and the removal of the individual bars permitted, substantially as set forth.
  - 15 2. The herein-described traveling grate, consisting of the combination of two or more series of transverse bars, said bars being joined to one another by continuous pivots, which also connect the different series with one another, substantially as set forth.
  - 20 25 3. The herein-described traveling grate, consisting of the combination, with the transverse bars pivoted together to form an endless car-

rier, and having the downwardly-projecting links f , of intermediate supporting-rollers recessed to fit said projections, substantially as set forth.

4. The herein-described traveling grate, consisting of the combination of two or more endless carriers formed of grate-bars, said carriers being arranged side by side, and connected by means, substantially as described, with one another, and intermediate supporting-rollers arranged on the line or lines of juncture of said carriers, substantially as set forth.

5. The herein-described traveling grate, consisting of the combination of two or more series of transverse bars, said bars being joined to one another by continuous pivots, which also connect the different series with one another, and an intermediate supporting roller or rollers arranged on the line of juncture of the different series, substantially as set forth.
